VALVE STEM GRINDER

John M. Krohn, Racine, Wis.

Application April 5, 1935, Serial No. 14,938

14 Claims. (Cl. 51—131)

This invention relates to grinding machines which are particularly adapted to grind the excess length from rods such as valve stems.

When the valves of an automobile are ground an adjustment must be made to the length of the valve stem. Where the stem is not adjustable as in the case of the cars manufactured by the Ford Motor Car Company, the end of the valve stem must be ground off. When this is done the mechanic measures the amount to be ground off with a feeler gage and grinds it by hand, estimating when he has ground off enough, and fits it by a cut and try method.

One object of this invention is to produce a valve stem grinder which may be set to grind off the necessary amount of the valve stem while rotating the stem and which will cease the grinding when the stem is the proper length.

Another object is to produce a valve stem grinder having an improved valve holder which rotates the stem while grinding.

Further objects are to produce a valve stem grinder which is simple to use and which will reduce the time and labor and increase the accuracy of setting the valve.

Other objects will become apparent upon consideration of the following specification.

In the drawings:

Fig. 1 is a horizontal cross-section of a valve stem grinder embodying the principles of the invention, and is a cross-section on the line 1—1 of Fig. 2.

Fig. 2 is an end elevation of the grinder shown in Fig. 1 with parts broken away on the lines 2—2' and 2''—2'' of Fig. 1.

Figs. 3, 4 and 5 are cross-sections on the lines 3—3, 4—4 and 5—5 respectively, of Fig. 1, looking in the direction of the arrows.

Referring to the drawings, in which like numerals indicate like parts throughout the several views, the grinder is shown mounted on a base 10 with a motor driven emery wheel 11, a holding and feeding mechanism generally designated 12 and a valve stem guide 13.

The emery wheel 11 is driven by a motor 15, with a shaft 16 projecting through the stone 11 and secured thereto by a nut 17, which screws into a recess 18 in the stone. A facing tool 20 slidably mounted in a standard 21 maintains the grinding face of the stone perpendicular to the motor shaft and the stem of a valve 23 which is being ground.

The holding and feeding mechanism which has been designated 12 is mounted in and on a housing 25 which has a cover plate 26 closing the

rear of the housing. The housing 25 has a bearing 27 which rotatably receives and guides a spindle or feeding head 28. The head 28 has one or more recesses 29 formed therein, as shown in Figs. 1 and 3, which receive the head of the valve 23 while the stem of the valve is held and guided by the valve stem guide 13. A bolt 19 is threaded through the head from the end opposite the recesses 29 and engages the head of the valve to hold it in place while it is being fed into the grinding wheel.

The outer end of the spindle or feeding head 28 projects through an elongated opening 30 in the cover plate 26, as shown in Fig. 3, which permits the valve head to enter the housing 25 and be inserted in a slot 31 in the feeding head 28.

A gear 32 is formed on the head 28, which is rotated by a driving gear 33. The gear 33 has annular plates 34—34 fixed on its sides which project past the outer edge of the gear teeth and engage the sides of the gear 32 so that axial movement of the gear 33 is transmitted directly to the gear 32 and causes a corresponding movement of the head 28.

The gear 33 is formed on a shaft 35 which is mounted in a bearing 36 in the housing 25. The shaft 35 is turned by a handle 37 outside the housing 25.

The end of shaft 35 opposite the handle 37 is provided with a cylindrical bore 38 which terminates in a co-axial threaded hole 39. A piston 40 fits into the cylinder 38 and forms a guide for that end of the shaft 35. The piston has a co-axial screw 41 thereon which engages with the threads in the opening 39 to advance the gear 33 in the housing 25.

The piston 40 is held fixed in a standard 42 and is held against rotation therein by a key 43 and against axial movement by a nut 44.

As the shaft 35 is rotated through the handle 37 the screw 41 engages the threads in the hole 39 and causes a corresponding lineal movement of the gear 33 which transmits the same lineal movement to the gear 32 through the annular plates 34—34. The axial movement of the head 28 depends on the pitch of the screw 41. If, for example, that screw contains twenty five threads per inch, each full turn of the handle 37 advances the head 28 four hundredths of an inch, and portions of a turn advance the head in proportion.

A dividing head, generally designated 43', is mounted on the housing 25 surrounding the feeding head 28, and is adapted to limit the rotation 55.

of the head 28 to a predetermined angle in the manner described below.

The dividing head 43' has an annular ring 45 fixed to the housing 25 concentrically with the head 28. The ring 45 has an annular recess formed on the inside surface adjacent the housing 25, which rotatably receives an annular projection or flange 46 on a cylinder 47 the member 46-47 constituting a dividing plate. The flange 46 has a plurality of holes 48 at equal intervals about the periphery which are adapted to be engaged by a spring pressed plunger 48'. The number of holes is a matter of convenience. For example, if one revolution of the head 28 advanced it four one hundredths as in the above example, forty holes would permit the valve stem to be ground to one thousandth of an inch.

The interior of the cylinder 47 receives a collar 50 which abuts against a shoulder 51 on the tail end of the feeding head 28 and is adapted to be held against movement relative to the feeding head by a pair of nuts 52 threaded on an extension 53. The collar 50 carries a spring pressed plunger 54, which is adapted to engage a stop hole 55 and stop the rotation of the feeding head 28.

The plunger is adapted to be held out of engagement with the hole 55 by a pin 56 which normally fits in a slot 57 in the collar 50 and which engages the outer edge of the collar when the plunger is withdrawn from the cylinder and turned at right angles.

A handle 58 is provided on the cylinder 47 to facilitate the turning thereof, and a pointer 59 indicates on a scale 60 on the ring 45, the setting of the plunger 46.

Operation

In operation, after the amount to be ground off the valve stem has been determined by a feeler gage, the valve stem is secured in the valve guide 13 with the valve head in one slot 29. The bolt 19 is screwed down on the head of the valve and secured against loosening by the lock nut. The nuts 52 may then be loosened which disengages the dividing head 43'. The handle 37 is turned to advance the shaft 35 on the screw 41, which advances the feeding head 28 until the end of the valve stem touches the stone 11. The nuts 52 are tightened securing the collar 50 to the feeding head 28. The plunger 54 is then withdrawn from the port 55 and held out of engagement by turning the handle until the pin 56 rests on the outer edge of the collar 50. The plunger 48' is withdrawn from the port 48 and the cylinder 47 rotated until the indicator 59 shows the desired cut on the scale 60.

Moving the cylinder moves the port 55 out of alignment with the plunger 54. Both plungers 48' and 54 may then be released. The plunger 48' engages in a port 48 while the plunger 54 rides on the plate forming the inner end of the cylinder 47. The valve stem is ground by turning the handle 37 which advances the stem onto the rotating stone 11. When the required amount has been removed, the plunger 54 again comes into alignment with the port 55, and permits the spring 53' to engage the plunger 54 in the port 55 and stop further rotation of the stem.

It is realized that this invention is susceptible to various changes and modifications and it is not, therefore, desired to limit the invention to the precise form herein shown and described but only by the scope of the appended claims.

What is claimed as new and desired to secure by Letters Patent is:

1. A valve stem grinder of the character described comprising, a base, a grinding stone on said base, a feeding head to hold a valve supported from said base and adapted to move longitudinally when rotated, a screw fixed to said base, a member having screw threads engaging said screw and advancing thereon upon rotation of said member, and means to transmit said rotation and said advancing movement to said feeding head whereby the stem of the valve is advanced onto said stone to be ground. 5

2. A valve stem grinder of the character described comprising, a base, a grinding stone 15 mounted on the base and adapted to grind a valve stem, a feeding head adapted to hold the valve and feed the stem onto the stone, a screw adapted to advance the feeding head while the head is being rotated, a dividing head surrounding the 20 feeding head, and means to releasably secure the dividing head to the feeding head.

3. In a grinder of the character described, a base, a standard mounted on said base, said base and said standard constituting a fixed member, 25 a spindle mounted for rotational movement in said standard, a dividing plate mounted to rotate about said spindle, said plate having a plurality of apertures therein, a stop member mounted on said fixed member and engageable with certain 30 of said apertures, and a second stop member rotatable with said spindle and engageable with another of said apertures to limit the rotational movement of said spindle.

4. In a grinder of the character described, a 35 base, a standard mounted on said base, said standard and said base constituting a fixed member, a spindle mounted for rotational and axial movement in said standard, means to move said spindle axially in proportion to the rotation 40 thereof, a dividing plate mounted to rotate about said spindle, said plate having a plurality of apertures therein, a stop member mounted on said fixed member and engageable with certain of said apertures, and a second stop member rotatable with said spindle and engageable with another of said apertures to limit the rotational movement of said spindle. 45

5. In a grinder of the character described, a base, a standard mounted on said base and constituting with said base a fixed member, a spindle mounted for rotational movement in said standard, means to hold a work piece in said spindle, a dividing plate mounted concentrically about said spindle and adapted to rotate relative 50 thereto, said plate having a plurality of first named apertures arranged on a circumference thereof and a second named aperture spaced from said first named apertures, a stop member mounted on said fixed member and engageable 55 with said first named apertures to fix the angular position of the plate, and a second stop member rotatable with said spindle and engageable with said second named aperture to limit the rotational movement of the spindle. 60

6. In a grinder of the character described, a base, a grinding stone mounted on said base, a standard mounted on said base, said base and said standard constituting a fixed member, a spindle mounted for rotational and axial movement in said standard, means on said spindle to hold a work piece, means to move said spindle axially in proportion to the rotation thereof, a dividing plate mounted concentrically about said spindle and adapted to rotate relative thereto, 70 75

said plate having a plurality of first named apertures arranged on a circumference thereof and a second named aperture spaced from said first named apertures, a stop member mounted on said fixed member and engageable with said first named apertures to fix the angular position of the plate, and a second stop member rotatable with said spindle and engageable with said second named aperture to limit the rotational movement of the spindle.

7. In a grinder of the character described, a base, a grinding stone mounted on said base, a standard mounted on said base, said base and said standard constituting a fixed member, a spindle mounted for rotational and axial movement in said standard, means on said spindle to hold a work piece, a screw drive adapted to advance the spindle in proportion to the rotation thereof, a dividing plate mounted concentrically about said spindle and adapted to rotate relative thereto, said plate having a plurality of first named apertures arranged on a circumference thereof and a second named aperture spaced radially inward from said first named apertures, a stop member mounted from said fixed member and engageable with said first named apertures to fix the angular position of the plate, and a second stop member rotatable with said spindle and engageable with said second named aperture to limit the rotational movement of the spindle.

8. In a grinder of the character described, a base, a standard mounted on said base and constituting with said base a fixed member, a spindle mounted for rotational movement in said standard, means on said spindle to hold a work piece to be ground, a dividing plate mounted to rotate about said spindle, said plate having a plurality of apertures therein, a stop member mounted on said fixed member and engageable with certain of said apertures to limit the rotational movement of the plate, a support releasably secured on said spindle, and a second stop member carried by said support and engageable with one of said apertures to limit the rotational movement of the spindle.

45 9. In a grinder of the character described, a base, a standard mounted on said base and constituting with said base a fixed member, a spindle mounted for rotational and axial movement in said standard, means to move said spindle axially in proportion to the rotation thereof, a dividing plate mounted to rotate about said spindle, said plate having a plurality of apertures therein, a stop member mounted on said fixed member and engageable with certain of said apertures to limit the rotational movement of the plate, a support releasably secured on said spindle, and a second stop member carried by said support and engageable with one of said apertures to limit the rotational movement of said spindle.

60 10. In a grinder of the character described, a base, a standard mounted on said base and constituting with said base a fixed member, a spindle mounted for rotational movement in said standard, means for holding a work piece in said spindle, a dividing plate mounted concentrically about said spindle and adapted to rotate relatively thereto, said plate having a plurality of first named apertures arranged on a circumference thereof and a second aperture spaced from said other apertures, a stop member mounted on said fixed member and engageable with said first named apertures to fix the angular position of the plate, a support releasably secured to said spindle, and a second stop member carried by said sup-

port and engageable with said second named aperture to limit the angular movement of said spindle.

11. In a grinder of the character described, a base, a grinding stone mounted on said base, a standard mounted on said base, said base and said standard constituting a fixed member, a spindle mounted for rotational and axial movement in said standard, means on said spindle to hold a work piece, means to move said spindle axially in proportion to the rotation thereof, a dividing plate mounted concentrically about said spindle and adapted to rotate relative thereto, said plate having a plurality of first named apertures arranged on a circumference thereof and a second named aperture spaced from said first named apertures, a stop member mounted on said fixed member and engageable with said first named apertures to fix the angular position of said plate, a support releasably secured to said spindle, and a second stop member carried by said support and engageable with said second named aperture to limit the rotational movement of the spindle.

15 12. In a grinder of the character described, a base, a grinding stone mounted on said base, a standard mounted on said base, said base and said standard constituting a fixed member, a spindle mounted for rotational and axial movement in said standard, means on said spindle to hold a work piece, a screw drive adapted to advance the spindle in proportion to the rotation thereof, a dividing plate mounted concentrically about said spindle and adapted to rotate relative thereto, said plate having a plurality of first named apertures arranged on a circumference thereof and a second aperture spaced radially inward from said first named apertures, a stop member mounted from said fixed member and engageable with said first named apertures to fix the angular position of the plate, a support releasably fixed to said spindle, and a second stop member carried by said support and engageable with said second named aperture to limit the rotational movement of the plate and hence the grinding action.

20 13. In a grinder of the character described, a base, a standard mounted on said base and constituting with said base a fixed member, a grinding stone mounted on said base and spaced from said standard, a spindle mounted for rotational movement in said standard, means on said spindle to hold a work piece, a dividing plate mounted to rotate about said spindle, said plate having a plurality of first named apertures arranged on a circumference in said plate, a cylindrical extension on said plate, said plate having a second named aperture therein within said cylinder, a second cylinder mounted within said first cylinder and on said spindle, means to releasably fix said second cylinder to said spindle to rotate therewith, a stop member mounted on said fixed member and engageable with said first named apertures to fix the angular position of said plate relative to said fixed member, and a second stop member carried by said second cylinder and engageable with said second named aperture to limit the angular movement of the spindle.

25 14. In a grinder of the character described, a base, a standard mounted on said base and constituting with said base a fixed member, a grinding stone mounted on said base and spaced from said standard, a spindle mounted for rotational and limited axial movement in said standard, screw impelling means adapted to effect axial move-

30 75

ment of said spindle in proportion to the rotation thereof, means on said spindle to hold a work piece, a dividing plate mounted to rotate about said spindle, said plate having a plurality of first named apertures arranged on a circumference in said plate said plate having a second named aperture therein spaced radially inward from said other apertures, a cylindrical extension on said plate concentric with said spindle the wall of 5
10 which passes between the first and second named

apertures, a second cylinder mounted within said first cylinder and on said spindle, means to releasably fix said second cylinder to said spindle to rotate therewith, a stop member on said fixed member engageable with said first named apertures to fix the angular position of said plate, and a second stop member carried by said second cylinder and engageable with said second named aperture to limit the rotation of the spindle. 5

JOHN M. KROHN. 10
